(57) CLAIM

The ornamental design for lower body garment, as shown and described.

DESCRIPTION

FIG. 1 is a perspective view of lower body garment showing my new design;

FIG. 2 is a front elevational view; the rear elevational view being identical thereof;

FIG. 3 is a side elevational view thereof;

FIG. 4 is another side elevational view thereof;

FIG. 5 is a top plan view thereof; and,

FIG. 6 is a bottom plan view thereof.

The broken line showing of environment is for illustrative purposes only and forms no part of the claimed design.
